UNITED STATES PATENT OFFICE.

ALBERT F. FIFIELD, OF ELIZABETH, NEW JERSEY, ASSIGNOR TO THE SINGER MANUFACTURING COMPANY, A CORPORATION OF NEW JERSEY.

SEWING-MACHINE.

1,152,498.

Specification of Letters Patent.

Patented Sept. 7, 1915.

Application filed March 18, 1911. Serial No. 615,193.

To all whom it may concern:

Be it known that I, ALBERT F. FIFIELD, a citizen of the United States, residing at Elizabeth, in the county of Union and State of New Jersey, have invented certain new and useful Improvements in Sewing-Machines, of which the following is a specification, reference being had therein to the accompanying drawings.

This invention relates more particularly to an improvement in that class of straight-away stitching machines which are provided with means for severing the thread or threads at the completion of each seam, as exemplified in the United States Patent to R. W. Thomson, No. 660,130, of October 23, 1900, and it has for its object to simplify and otherwise improve the construction of machines of this class.

The machine is designed more particularly for sewing tongues to the vamps of lace shoes and also for toe-closing the linings of shoes, although adapted for many other kinds of stitching operations.

In its preferred form the mechanism comprises stitch-forming means including a rectilinearly reciprocating needle in conjunction with a well known form of four-motion feeding mechanism, and is provided with thread-cutting mechanism and a stop-motion device controlled by a common cam-wheel, as in the United States Patent to C. M. Horton No. 807,676, of December 19, 1905.

The special feature of the present improvement is the provision of manually controlled coupling means whereby the actuating cam may be coupled to and uncoupled from its driving means at the will of the operator, the machine being adapted to run during ordinary stitching operations substantially as lightly and quietly as the ordinary straight-away stitching machine, the cutter and stop-motion actuating means being normally stationary during the stitching operations.

In the accompanying drawings, Figure 1 is a perspective view, partly in section, of a sewing machine embodying the present improvements, Fig. 2 a front end view of the same with the face-plate of the bracket-arm removed, and Fig. 3 a bottom plan view of the machine. Fig. 4 is a detail sectional elevation of a portion of the stop-motion

device and Fig. 5 a detail perspective view of the stop-motion tripping means. Figs. 6, 7, 8 and 9 represent the coupling means for connecting the actuating cam with its continuously rotating driving member, Fig. 6 being a face view of the coupling disk, Fig. 7 a transverse section of the same, Fig. 8 also a transverse section thereof on the line $\alpha\alpha$ of Fig. 6, with the coupling disk and feed-wheel slightly separated, and Fig. 9 a perspective view of the coupling disk and its spring detached from the other parts. Fig. 10 is an elevation showing in detail a portion of the controlling means for the coupling-disk and cam-wheel detents. Fig. 11 is a perspective view of the thread-cutting knives and sector-gear by which they are carried.

The frame of the machine comprises the usual bed-plate 1 and bracket-arm comprising the hollow standard 2 and lateral arm 3 terminating in the head 4, in which is journaled the main-shaft 5 carrying the fast and loose pulleys 6 and 7 respectively. The main-shaft has fixed upon its forward end the crank-plate 8 carrying the crank-pin 9 connected by the pitman 10 with the rectilinearly reciprocating needle-bar 11 journaled in the head 4 of the bracket-arm and carrying the needle 12. Coöperating with the needle beneath the throat-plate is the oscillating shuttle 13 provided with the thread-case 14 and fitted within the shuttle-race 15. The shuttle is actuated by means of the driver 16 fixed upon the forward end of the rock-shaft 17 journaled beneath the bed-plate and provided with operative connections, as in the well known Singer oscillating shuttle machines, with the actuating crank 18 of the main-shaft.

Opposed to the presser-foot 19 secured to the usual spring-pressed presser-bar 20 journaled in the head 4 of the bracket-arm is the feed-dog 21 which is carried by the feed-bar 22 deriving its to-and-fro feeding movements from the feed-actuating rock-shaft 23 having operative connections with the main-shaft, including the link-bar 24 forked at its upper end to embrace the slide-block 25 upon the feed-actuating eccentric carried by the main-shaft, while the feed-bar has a connection with the lateral arm 26 of the feed-lifting rock-shaft 27 also operatively connected by means of the crank-

arm 28 and pitman 29 with an eccentric 30 upon the main-shaft.

As shown more fully in the said United States Patent No. 807,676, the stop-motion 5 comprises a swinging lever 31 having its lower end pivotally mounted in the oscillatory fulcrum block 32 to swing in the plane of the main-shaft and transversely thereof. It is provided with a vertical socket 33 in which 10 is fitted the plunger 34 having the wedge-shaped nose 35 adapted for engagement with the stopping cam 36 provided with the peripheral notch 37 and adjacent shoulder 38, the plunger being normally pressed upwardly by means of the spring 39 within 15 the socket 33, as represented more particularly in Fig. 4. Secured to the lever 31 by means of the screw 40 is the fork 41 embracing the driving belt and adapted to 20 shift it from one to the other of the pulleys upon the main-shaft.

The lever 31 is normally pressed backwardly to bring the plunger 34 into operative relation with the cam 36 by means of 25 a spring interposed between the same and the standard 2 of the bracket-arm, and is shifted forwardly out of operative relation with the stopping cam by means of a bell-crank fulcrumed upon the screw-pin 42 30 within the bracket 43 and having a depending arm 44 resting against the rearward edge of the lever and a lateral arm 45 provided with an eye 46 for attachment of a treadle-rod by means of which the bellcrank 35 is rocked to disengage the plunger from the cam 36 and ship the belt from the loose pulley to the fast pulley in starting the machine. Fulcrumed upon the stud-screw 47 above the bracket 43 is a latch-lever 48 40 whose hooked rearward end is adapted to engage the foot 41^x of the belt-shipper fork and whose opposite end is disposed in register with one end of the transversely arranged push-pin 49 journaled within the bearing member 50 secured upon the standard 2 and limited in its endwise movements by means of the pin 51 working in the slot 52 of the bearing member 50. The latch-lever 48 is normally pressed into operative 45 relation with the stop-lever by means of the spring 53 surrounding the fulcrum-stud 47.

The push-pin 49 is operated to trip the latch-lever 48 by engagement with the inclined tripping plate 54 having in one end the slot 55 through which passes the fastening screw 56 by which it is adjustably secured upon the recessed inner face of the cam-wheel 57 whose hub 58 is journaled upon the tubular hub 59 of the driven gear-wheel 60 journaled upon the fixed screw-stud 61 tapped into the bracket-arm, the gear 60 meshing with an actuating pinion 62 fixed upon the transverse shaft 63 suitably journaled in the bracket-arm and provided with a bevel pinion 64 meshing with

a similar pinion 65 which is fixed upon the main-shaft.

As shown and described in the said Patent No. 807,676, the upper and lower thread-cutting knives 66 and 67 are secured to a sector-gear 68 journaled in a bracket 69 attached to the shuttle-race cover-slide 70. These knives have plural-stage actions for initially engaging and positioning the upper and lower threads and thereafter severing them in a subsequent stage of operation. Meshing with said sector-gear is a rack 71 carried by a sliding bar 72 arranged beneath the work-plate and having near its rear end the block 73 formed with a notch entered by the reduced lower end 74 of a lever 75 pivotally mounted upon a fixed stud-screw 76 and provided at its upper end with the roller-stud 77 entering the cam-groove 78 in the outer face of the cam-wheel 57. The bar 72 carries at its rear end the stud 79 engaged by the forked arm 80 of a bell-crank-lever fulcrumed at 81 and having another arm 82 provided with a plunger-pin 83 having a stud 83^x engaged by the spring 84 tending to press the pin outward into the slot 85 in the lower end of the depending arm 86 secured upon the stop-lever 31. The bracket 43 has a lateral socket 87 to which is fitted the head 88 of a buffer-pin surrounding whose reduced shank is the spring 89 interposed between the head and the threaded bushing 90 locked adjustably in the outer end of said socket by means of the set-nut 91.

Coupling means are provided whereby the cam-wheel 57 is normally connected for rotation in unison with the driving gear 60, which is connected with the main-shaft through the gearing before described so as to perform one rotation for each ten rotations of the main-shaft, and the tripping plates 54 of the stop-motion device are duplicated and the cam-grooves 78 of each semi-circumference of the cam-wheel are 110 alike, so that the stop-motion and thread-cutting mechanisms are both actuated twice for each rotation of the cam-wheel.

The outer face of the driving member 60 is provided with an annular series of recesses or notches 92 adapted to receive the adjacent ends of the coupling pins 93 fitted within sockets 94 in the hub portion of the cam-wheel 57 and having interposed between their enlarged heads and inner ends of the sockets the springs 95, while to their reduced outer ends, projecting beyond the sockets 94 are secured by means of the transverse pins 96 the cam-blocks 97 formed with lateral wings or extensions 98 having inclined inner faces engaging the similarly inclined cam-inclines 99 formed within segmental slots 100 of the coupling disk 101 fitted loosely upon the hub 58 of the cam-wheel 57. The disk 101 has in its inner face 130

the annular groove 102 to receive the spring 103 one end of which rests against a pin 104 within said slot and the other end engages a pin 105 projecting into said groove 5 from the adjacent face of the cam-wheel 57. The action of the spring 103 is normally to turn the disk 101 into such position upon the cam-wheel that the pin 104 rests in contact with the stop-pin 106 also projecting 10 from the cam-wheel into the groove 102. In this position of the coupling disk the cam-blocks 97 are permitted to move down the cam-inclines 99 to enable the coupling pins 93 under the action of their springs 94 15 to enter their recesses or pockets 92 in the driving member for coupling the cam-wheel with the latter. The slots 100 of the coupling disk are covered by means of an annular plate 107 secured thereon by means 20 of screws 108.

The disk 101 is provided at diametrically opposite points with the peripheral notches 109 to afford shoulders for engagement with the flattened and outwardly curved upper 25 end 110 of an arm 111 whose hub 112 is secured upon the pin 113 within the forked bearing bracket 114 secured upon the bed-plate. The pivotal pin 113 has also fixed 30 thereon the hub of an upwardly extending arm 115 having at its upper end a lateral pin 116 entering a longitudinal slot 117 in the forward end of a link 118 which is pivotally attached at its opposite end by means 35 of the screw-pin 119 to an elbow-lever 120 rigidly connected with the stop-motion actuating bell crank-lever 44 45, said elbow-lever having a forwardly extending arm to which is connected one end of the spring 121 whose opposite end is attached to a hook 122 40 secured to the base of the bracket-arm standard. The arm 115 is connected with one end of a spring 123 whose opposite end is attached to a stud 124 secured to the standard 2 and adapted to normally draw 45 said arm forward to press the arm 111 into operative relation with the periphery of the disk 101.

The cam-wheel 57 is provided with the 50 diametrically arranged peripheral notches 125 adapted to be entered by the lateral tooth 126 upon the flattened upper end of the plunger-rod 127 which is formed in its lower portion with an enlargement 128 fitted within a socket 129 in the tubular arm 130 having its hub 131 secured by means of a set-screw 132 upon the pivotal pin 133 within the forked bracket-piece 134 secured upon the bed-plate 1. In the upper end of the 55 socket 129 is introduced the bushing 135 serving as a stop against which the upper end of the enlargement 128 of the plunger-rod 127 is pressed by means of the spring 136 interposed between the lower end of the portion 128 and the bottom of the socket 129, 60 a transverse pin 137 being applied to the

part 128 and working in a lateral slot 138 in the member 130 to prevent the plunger-rod from turning.

Upon the inner end of the pivotal pin 133 is secured the hub of the upwardly extending arm 139 carrying the lateral pin 140 entering a longitudinal slot 141 in the forward end of a link 142 which is pivotally attached at its opposite end by means of the screw-pin 119 to the elbow-lever 120. 70 The arm 139 is connected with one end of a spring 143 whose opposite end is attached to a stud 144 secured to the standard 2 and adapted to normally draw said arm forward to press the plunger-rod 127 into operative 80 relation with the periphery of the cam-wheel 57. The spring 121 serves to normally maintain the stop-motion actuating bellcrank in inoperative position with the arm 44 retracted from operative relation with the 85 stop-lever 31, and this spring is sufficiently strong to counteract the effect of the springs 123 and 143 tending to draw the members 111 and 127 into operative relation with the coupling disk 101 and cam-wheel 57 by engagement of the pins 116 and 140 with the forward extremities of their respective slots in the links 118 and 142. When such bellcrank is operated in opposition to its spring 121 in starting the machine, 90 the forward movement of the links 118 and 142 serves to release the pins 116 and 140 from operative engagement with the ends of the slots 117 and 141 so as to permit the springs 123 and 143 to act in drawing the 100 members 111 and 127 into operative relation with their respective cam-members.

When the machine is at rest, at the completion of a stitching operation, the cutting blades 66 and 67 remain in their final thread-engaging position which they assume under the action of the rock-lever 75, preparatory to the final cutting action induced by the overthrow of the machine in coming to rest under the operation of the stop-motion, the 105 needle being in raised position. In starting the machine, the bellcrank-arm 45 is depressed by means of the usual treadle connection to bring the arm 44 into forcible engagement with the stop-lever 31 which is 110 shifted forwardly to disengage the plunger 34 from the stopping cam 36 and simultaneously shift the belt from the loose pulley 7 to the fast pulley 6. By this action, the links 118 and 142 are advanced to release the arms 115 and 139, whereby the rods 111 and 127 are caused to rest upon the peripheries of their respective cam-members, this relation of the parts referred to being maintained so long as the bellcrank-arm 45 is held down by the operator. Under the conditions described, the main-shaft is coupled with the source of power and the stitching proceeds 115 continuously and the driving gear-wheel 60 performs its continuous rotary movements 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 throughout the period of movement of the main-shaft to which it is permanently geared.

Under the action of the spring 103 upon the coupling disk 101, the coupling pins 93 are normally pressed by their springs 95 into the recesses or pockets 92 of the driving member 60, so that in the initial action of the stitch-forming mechanism the cam-wheel 57 and coupling disk 101 are caused to rotate with the driving member 60. During the rise of the needle after its initial descent, the engagement of the stud 77 with the part 78^a of the cam-groove 78 causes the movement of the rock-lever 75 to produce the initial retractive movement of the cutter-blades 66 and 67 to intermediate position wherein their respective points are at opposite sides of the needle-hole, and during the rise of the needle after its second descent, the action of the portion 78^b of the cam-groove 78 upon the rock-lever 75 produces the second stage of the retrograde movement of the cutter-blades into retracted position, as represented in Fig. 3.

Immediately after the described retractive movement of the cutter-blades, the engagement of the nose 110 of the detent-arm 111 with one of the shoulders 109 of the coupling disk causes the arrest of the movement of the latter while the cam-wheel 57 continues to rotate with its driving member 60, and carrying the coupling pins 93 around with it so as to cause the blocks 97 to ride up the cam-inclines 99 of the now stationary disk 101 for withdrawal of the pins 93 from their respective pockets 92 in the driving member 60 for disconnecting the cam-wheel from the latter. During the retraction of the cam-pins 93, the rotation of the wheel 57 brings its peripheral notches 125 into register with the tooth 126 of the detaining plunger-rod 127 which snaps into the same to lock the cam-wheel against further rotation, as represented in Fig. 1. The retraction of the coupling pins is not completed until the action of the detaining member just described, and to compensate for any difference in timing of the uncoupling of the cam-wheel from its driving member and its engagement with its detaining member 127, the buffer-spring 136 is employed, so as to permit the cam-wheel 57 to have a slight advance movement after its engagement by the detaining member 127 during which the uncoupling may be completed.

While the bellcrank-arm 45 is held down by the operator the cam-wheel 57 continues to be uncoupled from its continuously rotating driving member 60 and the stitching and feeding mechanisms continue in operation to produce a seam of any desired length. The completion of the seam is performed at will by the operator's merely releasing the bellcrank-arm 45, whereby the spring 121 is caused to throw the bellcrank into re-

tracted inoperative position, whereby through the links 118 and 142 the detaining members 111 and 127 are retracted from their respective cam-members. The release of the cam-disk 101 permits its spring 103 to give it a slight advance movement to relieve the pressure of the cam-inclines 99 upon the wings 98 of the blocks 97, thereby permitting the springs 95 to force the coupling pins 93 outwardly into contact with the face of the driving member 60 and to enter the coupling pockets 92 therein as soon as they come into register with the coupling pins, thus reestablishing operative relation with the driving member 60 and cam-wheel 57.

As the cam-wheel reassumes its rotary movement, the traverse of the roller-stud 77 in the concentric portion 78^c of the cam-groove 78 causes the rock-lever 75 to remain in retracted position during the formation of the next stitch by the stitch-forming mechanism, but as the needle performs the initial part of its descent for the succeeding stitch, the movement of the stud 77 through the inclined portion 78^d of the cam-groove 78 causes the actuation of the rock-lever 75 to advance the cutter-blades 66 and 67 into intermediate position in which the blunt point of the lower-thread cutting blade 67 moves beneath the needle-hole in the throat-plate and engages the shuttle-thread leading through the same, the cutting members remaining in these positions until the needle is rising after its descent for the final stitch-forming operation, when the traverse of the stud 77 through the inclined portion 78^e of the cam-groove 78 produces through the rock-lever 75 the second stage of advance of the cutter-blades wherein the blunt point of the blade 66 enters the distended loop of needle-thread engaged by the shuttle, while the blade 67 causes the deflection of the shuttle-thread to draw off from the bobbin a sufficient supply for production of the initial stitch of the succeeding stitching operation.

Just as the stud 77 is traversing the cam-groove portion 78^d, one of the tripping plates 54 presses inwardly the push-pin 49 which causes the disengagement of the latch-lever 48 from the stop-lever 31 and permits the latter to assume stopping position with the nose 35 of the plunger 34 in readiness to snap underneath the low portion of the stopping cam 36 when presented thereto in the continued rotation of the main-shaft. As the stop-lever 31 is thrown backwardly under the operation of its spring (not shown) the arm 86 is thrown forwardly, thus pressing inwardly the plunger-pin 83 which is, in the intermediate position of the cutter-blades disposed at one side of the aperture 85. As the slide-bar 72 is moved in the completion of the second stage of the cutter movement, the plunger-pin snaps into

the aperture 85, thereby coupling the bell-crank 80-82 with the stop-lever 31. As the shoulder 38 of the stopping cam comes into engagement with the nose 35 of the plunger 34, the momentum of the main-shaft and parts connected therewith induces a slight overthrow which is resisted by the buffer-pin 88, and the lateral movement of the stop-lever arm 86 acts through the bell-crank 80-82 to impart to the slide-bar 72 a final jog which produces a third and final stage of advance of the cutter-blades which brings their cutting edges 66^x and 67^x, respectively, arranged near the heels of such blades, into contact with the upper and lower threads, whereby the latter may be severed. To permit this final movement under the action of the stop-motion device, the cam-groove 78 of the cam-wheel 57 is provided with lateral clearance pockets 78^z into which the stud 77 of the rock-lever 75 is permitted to move freely under the actuation of the slide-bar 72.

While in the present embodiment of the improvement several stitches are made in a cycle of operation of the cam-wheel between stopping points corresponding with the diametrically disposed recesses 78^z of the cam-groove 78, this feature is unobjectionable in the class of work for which the machine is particularly designed, as the operator is enabled to readily cause the stoppage of the machine upon the desired stitch by releasing the stop-lever operating bellcrank a few stitches before the desired action is to take place.

One of the important advantages of this improvement is the disconnection from the driving shaft of the actuating means for the cutting mechanism and stop-motion, so that the machine may be operated as an ordinary straightaway stitching machine excepting at the beginning and end of a seam wherein it insures the arrest of the stitch-forming mechanism with the needle raised and the cutting of both threads beneath the work, thus saving any manipulation of the machine preparatory to introducing and removing the work and the loss of thread and the time for cutting apart successively stitched articles, which has been usual heretofore.

It is evident from the nature of the improvement as set forth in the foregoing description that it is susceptible of material modification in the construction and arrangement of its various component parts, and that the invention is not therefore limited to the specific embodiment herein shown and described.

Having thus set forth the nature of the invention, what I claim herein is:—

1. In a sewing machine, the combination with stitch-forming mechanism, of thread-cutting mechanism, a cam for controlling

the operation of the thread-cutting mechanism, actuating means for said cam, a coupling device between said cam and its actuating means, and manually controlled means adapted for engagement with said cam independently of the coupling device whereby the latter is caused to couple and uncouple said cam and its actuating means. 70

2. In a sewing machine, the combination with stitch-forming mechanism and a stop-motion for controlling the action of the same, of thread-cutting mechanism, a cam for tripping the stop-motion to arrest the stitch-forming mechanism and actuating the cutting mechanism, and manually controlled 80 means whereby said cam is thrown into and out of operation. 75

3. In a sewing machine, the combination with stitch-forming mechanism and a stop-motion for controlling the action of the same, of a thread-cutting mechanism, a cam provided with means for tripping the stop-motion to arrest the stitch-forming mechanism, a connection between said cam and the thread-cutting mechanism for imparting to 90 the latter initial thread-engaging action, a connection between said stop-motion and the cutting mechanism through which the latter receives a final thread-cutting movement, actuating means for said cam, a coupling between said cam and its actuating mechanism, and manually controlled means for operating said coupling device in coupling together and uncoupling said cam and its actuating means. 95

4. In a sewing machine, the combination with stitch-forming mechanism including a needle and loop-taking means, and actuating means therefor, of thread-cutting mechanism including a member adapted to engage 105 the thread intermediate the needle and loop-taking means, a rotary member for controlling the action of the thread-cutting mechanism, means connected with the actuating means of the stitch-forming mechanism for actuating said rotary member, and means for connecting and disconnecting said rotary member and its actuating means. 110

5. In a sewing machine, the combination with stitch-forming mechanism and actuating means therefor, of thread-cutting mechanism comprising a train of permanently connected elements, a rotary member for controlling the action of the same, means connected with the actuating means of the 115 stitch-forming mechanism and normally coupled with said rotary member whereby the latter is actuated, and manually operated means for disconnecting said rotary member and its actuating means and maintaining 120 such disconnection for stitching-periods of variable length. 125

6. In a sewing machine, the combination with stitch-forming mechanism, of thread-cutting mechanism, a controlling cam and 130

operative connections between the same and the thread-cutting mechanism whereby the latter is actuated, a continuously moving rotary driving member, coupling means between the same and said cam and comprising a coupling element carried by said cam, and a rotary member movable with and also independently of said cam and adapted for shifting said coupling element into and out of operative relation with the driving member, and means acting through said rotary member for causing the operation of said coupling element.

7. In a sewing machine, the combination with stitch-forming mechanism, of thread-cutting mechanism, a controlling cam and operative connections between the same and the thread-cutting mechanism whereby the latter is actuated, a continuously moving rotary driving member, coupling means between the same and said cam and comprising a coupling element carried by said cam and provided with a cam-follower and a rotary cam member movable with and also independently of said cam and provided with a cam portion adapted for engagement with the follower of said coupling element, a spring for normally maintaining said coupling element in operative position, and manually controlled means for locking said rotary cam member against movement while the controlling cam is in motion for retracting said coupling member from operative position.

8. In a sewing machine, the combination with stitch-forming mechanism, of thread-cutting mechanism, a controlling cam and operative connections between the same and the thread-cutting mechanism whereby the latter is actuated, a continuously moving rotary driving member, coupling means between the same and said cam and comprising a coupling element carried by said cam and provided with a cam-follower and a rotary cam member movable with and also independently of said cam and provided with a cam portion adapted for engagement with the follower of said coupling element, a spring for normally maintaining said coupling element in operative position, manually controlled means for locking said rotary cam member against movement while the controlling cam is in motion for retracting said coupling member from operative position, and means for detaining the controlling cam against rotation when uncoupled from its driving member.

9. In a sewing machine, the combination with stitch-forming mechanism, of thread-cutting mechanism, a controlling cam and operative connections between the same and the thread-cutting mechanism whereby the latter is actuated, a continuously moving rotary driving member, coupling means between the same and said cam and comprising

ing a coupling element carried by said cam and provided with a cam-follower and a rotary cam member movable with and also independently of said cam and provided with a cam portion adapted for engagement with the follower of said coupling element, a spring for normally maintaining said coupling element in operative position, manually controlled means for locking said rotary cam member against movement while the controlling cam is in motion for retracting said coupling member from operative position, and yieldingly acting means for detaining the controlling cam against rotation when uncoupled from its driving member.

10. In a sewing machine, the combination with stitch-forming mechanism, a stop-motion for controlling the action of the same, and a manually controlled actuator for operating the stop-motion to start the stitch-forming mechanism, of thread-cutting mechanism, a controlling cam provided with means whereby the stop-motion may be tripped to arrest the action of the stitch-forming mechanism and the thread-cutting mechanism may be actuated, a continuously moving rotary driving member, normally operative coupling means between the same and the controlling cam, and a connection between said coupling means and the actuator for the stop-motion for operating the coupling means to disconnect the controlling cam from its driving member while the stitch-forming mechanism is in action.

11. In a sewing machine, the combination with stitch-forming mechanism, of thread-cutting mechanism including a thread-engaging member movable in a path intersecting the range of action of the stitch-forming mechanism, controlling means for said thread-cutting mechanism, actuating means therefor, a coupling device between said controlling means and its actuating means, and manually controlled means independent of said actuating means for interrupting and establishing driving relation between the latter and said controlling means.

12. In a sewing machine, the combination with stitch-forming mechanism and actuating means therefor, of thread-cutting mechanism including a member having a path of movement within the range of action of the stitch-forming mechanism, controlling means including a rotary element having a driving connection with said actuating means and an operative connection with the thread-cutter whereby the latter may be actuated, and manually operated means for rendering said controlling means effective or ineffective at will.

13. In a sewing machine, the combination with stitch-forming mechanism and a stop-motion for controlling the action of the same, of thread-cutting mechanism, a cam

for tripping the stop-motion to arrest the stitch-forming mechanism and actuating the cutting mechanism, and manually operated means whereby the cam is rendered effective or ineffective at will in tripping the stop-motion and actuating the cutting mechanism.

14. In a sewing machine, the combination with stitch-forming mechanism, thread-cutting mechanism, and a stop-motion, of controlling means comprising a cam and connections between the same and the thread-cutting mechanism and stop-motion respectively, for effecting the cutting of the threads and arresting of the stitch-forming mechanism, and manually operated means for rendering said controlling means effective or ineffective at will.

15. In a sewing machine, the combination with a shaft, stitch-forming mechanism operatively connected therewith, and a stop-motion including a vibratory lever for controlling the operation of said shaft, of thread-cutting mechanism, connecting means between the thread-cutting mechanism and said shaft and including stop-motion tripping means, a connection between said vibratory lever and the thread-cutting mechanism, and manually controlled means acting upon said vibratory lever and through said connecting means in establishing and

interrupting operative relation between said shaft and the thread-cutting mechanism.

16. In a sewing machine, the combination with stitch-forming mechanism including a needle and a coöperating loop-taker, actuating means therefor, and a stop-motion for controlling the action of the same, of thread-cutting mechanism including successively acting thread-positioning and cutting means, connecting means between the thread-cutting mechanism and said actuating means for imparting to the thread-cutting mechanism an initial thread-positioning stage of its operation, said connecting means being provided with a stop-motion tripping element, an operative connection between the stop-motion and the thread-cutting mechanism through which the latter derives a final thread-cutting action, and manually operated means for maintaining the stop-motion inactive and said connecting means ineffective for a period controlled at the will of the operator.

In testimony whereof, I have signed my name to this specification, in the presence of two subscribing witnesses.

ALBERT F. FIFIELD.
